ATTORNEY.

UNITED STATES PATENT OFFICE.

MAX H. FEIST, OF TOUTLE, WASHINGTON.

DESIGN FOR AN ADVERTISING SIGN.

Application filed March 29, 1924. Serial No. 9,098. Term of patent 3½ years.

To all whom it may concern:

Be it known that I, MAX H. FEIST, a citizen of the United States of America, residing at Toutle, in the county of Cowlitz and State of Washington, have invented a new, original, and ornamental Design for an Advertising Sign, of which the following is a specification, reference being had to the accompanying drawings, forming a part thereof.

The figure is a front elevation illustrating my new design.

I claim:

The ornamental design for an advertising sign, substantially as shown.

MAX H. FEIST.
